CLAIM

We claim the ornamental design for a shoe, as shown and described.

DESCRIPTION

FIG. 1 is a bottom view of a shoe, showing our new, original and ornamental design;

FIG. 2 is a front view thereof;

FIG. 3 is a side view thereof;

FIG. 4 is a top view thereof;

FIG. 5 is a back view thereof;

FIG. 6 is an opposite side view thereof; and,

FIG. 7 is a perspective view thereof.

The consistent length broken lines showing portions of the article form no part of the claimed design. The dot-dash

(Continued)

broken lines indicate boundary lines between claimed portions and unclaimed portions and form no part of the claimed design.

1 Claim, 7 Drawing Sheets
